ADJUSTABLE VESSEL HOLDER FOR FIELD RANGES

George P. Wells, United States Army,
Chicago, Ill.

Application October 19, 1944, Serial No. 559,430

12 Claims. (Cl. 126—24)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

My invention relates to means for holding pots, pans, or other cooking vessels on the tops of stoves, and more particularly to a new and improved stopping means for use on mobile field ranges of the type used in the Army to prevent lateral shifting of the vessels when the stove is jostled about while it is being transported.

Various type of ranges are being used by the Army in its mobile field kitchens. Some of these ranges have flat tops upon which the pots, pans, or other cooking vessels are placed when being heated. It has been the practice to lash these vessels to the tops of the ranges with ropes or straps tied to the side rails of the range to prevent shifting or upsetting of the vessels when the trip is rough. This has been an unsatisfactory expedient because even though the lash ropes are tightly secured, the bottoms of the pots, pans, or other vessels are free to move laterally. As a result they may not be centered directly over the source of heat, and they may even move sufficiently to work loose from the lashings and upset. It is a principal object of my invention to provide a new and improved means for securing a cooking vessel on the top of a range to prevent lateral movement of the bottom of the vessel, no matter how much the range is jostled about.

Another object of the invention is to provide a new and improved means for securing pots, pans, or other cooking vessels on the top of a mobile field range which is adjustable to secure vessels of various sizes and shapes.

Another object of the invention is to provide new and improved means for securing pots, pans, or other cooking vessels on the top of a mobile field range which may be readily moved to operative or inoperative position by an operating handle provided for that purpose at the front of the range.

Another object of the invention is to provide a new and improved means for securing pots, pans, or other cooking vessels on the top of a mobile field range which may be adjusted to inoperative position, and which in that position is entirely clear of the top of the range, and does not interfere with the placing or movement of vessels on the range.

Another object of the invention is to provide new and improved means for securing pots, pans, or other vessels on the top of a field range which may be readily installed in the ranges of present

manufacture without radically changing the construction thereof.

Another object of the invention is to provide a new and improved means for securing the bottoms of pots, pans, or other cooking vessels on the tops of field ranges which is simple in construction, easy to operate and inexpensive to manufacture, yet sufficiently durable to withstand the rough usage to which such devices are likely to be subjected.

These and other objects of the invention will become apparent from the following description and accompanying drawings, in which:

Fig. 1 is a front elevational view of a field range showing the manner of securing pots on the top of the range making use of my invention.

Fig. 2 is a top plan view of a range with my improved vessel-holding means installed thereon.

Fig. 3 is a partial vertical section taken on the line 3—3 of Fig. 2.

Fig. 4 is a perspective view of the underside of a top plate of a range showing depending members in which the operating mechanism of my device is mounted.

Fig. 5 is a diagrammatic view of a pair of cams and the bevel gear arrangement for operating the cams.

Fig. 6 is sectional view taken on the line 6—6 of Fig. 1.

Fig. 7 is a diagrammatic view of a modified form of operating mechanism for the cams.

Fig. 8 is a partial section through the main bevel gear driving mechanism of the modification shown in Fig. 7.

Throughout the drawings like reference numbers indicate similar parts throughout the several views. In Fig. 1 I have shown diagrammatically a gas field range 10 of a type suitable for use in a mobile Army field kitchen. Ranges 40 of this type may also be used in the galleys of ships, and in such installations advantageous use can be made of my invention. When used in a mobile field kitchen the range is permanently mounted on a trailer or a truck upon which it is transported from place to place. It is apparent that on poor roads or when traveling cross-country the range will be subject to constant jostling, and even on a good modern highway a range so mounted will be subject to considerable jostling while being transported.

If the range is being used for cooking purposes while being transported, some means must be provided for preventing the pots, pans, or other vessels from sliding around on the top of the range. Heretofore, this has been accomplished by lash-

ing the pots, pans, or other vessels to the top of the stove by means of ropes or straps secured to the vessels and to the side rails 11 of the stove. This has been found to be unsatisfactory because the bottoms of the pots, pans, or other vessels are free to move laterally to a considerable extent when the terrain is rough or the journey long. As a result, the vessels are not held centrally over the source of heat, and it is always possible that they may work free from the lashing and upset.

To overcome this disadvantage, I have provided my new and improved holding or stopping means for preventing shifting of the bottom of a vessel. In the drawings my device is shown as adapted for use on a gas-burning field range, and the description will be limited to its application to such a range, even though it is apparent that by slight modification it may be adapted for use on ranges burning other fuels. The range 10 shown in Figs. 1 and 2 has a series of top plates 12, two being shown for illustrative purposes. These top plates are bolted or otherwise suitably secured to the frame of the range 10, so that they may be easily removed therefrom, and are provided with burner openings, those in the front being numbered 13, and those in the rear 14. Integral with the plate 12 and extending radially inwardly toward the center of the openings there-in are the arms 15, 16, 17 and 18 which are formed in opposed pairs. Pots, pans, and other cooking vessels are supported on these arms while being heated. For supplying heat for cooking purposes a gaseous fuel burner 19 of known construction is installed below each burner opening 13 and 14 with its arms positioned below the openings in the plate between the arms 15, 16, 17 and 18.

A series of apertures 20 are spaced on the longitudinal center line of the arms 15, 16, 17 and 18, four apertures being shown in each arm. The corresponding apertures in the different arms are located equi-distant from the center of the burner openings 13 and 14, and are spaced to correspond to the diameter of the standard sized pots or pans used in the Army. Pins or stops 21 are freely received in the apertures 20, a single pin or stop being placed in each of the four arms. Ordinarily they are placed in corresponding apertures in the arms, but they may be placed in non-corresponding apertures to accommodate non-circular vessels or non-standard vessels. Pins 21 fit loosely in apertures 20 and are supported by the structure shown in Figs. 3, 5 and 6 which will now be described.

For the sake of brevity, only the structure for one of the rear burners will be described, because a similar construction is used for the other burners in the range. For supporting the pins 21, elongated cams 22, 23, 24 and 25 are provided. These cams are rigidly secured on camshafts 26, 27, 28 and 29 which rotate in bearings 30—30, 31—31, 32—32 and 33—33 formed in brackets 34 on the underside of the top plate 12 and arms 66 depending from the edges of the plate at points oppositely disposed to the depending arms of the brackets 34. The camshafts are supported in a horizontal plane by this means immediately below the line of apertures 20 in the arms 15, 16, 17 and 18. When a pin 21 is placed in an aperture 20 it drops until the bottom end seats upon the face of a cam. The cams are of generally elongated oval shape in cross section, and are eccentrically mounted on the camshafts 26, 27, 28 and 29 as shown in Figure 5, so that when the cams

are rotated the pins 21 are reciprocated vertically. When the cams are in the position shown on the left of Figure 3, with the pins 21 resting on the low face of the cam, the top ends of the pins are flush with the top surface of the plate 12, and vessels may be freely moved about on the top of the range. When the cams are rotated through an angle of 180 degrees from the first mentioned position so that their humped sides are vertical, the pins are supported in an elevated position with the top ends projecting above the top of the plate 12 as shown on the right in Figure 3. In this position the pins are adapted to bear against the sides of a vessel 35 placed on the range as shown in Figure 1, thereby preventing the bottom of the vessel from shifting laterally on the range.

The mechanism for operating the cams 22, 23, 24, and 25 consists of bevel gears 36, 37, 38 and 39 non-rotatably secured on the inner ends of camshafts 26, 27, 28 and 29 respectively. These bevel gears mesh with the upper beveled portion of a double bevel gear 40, secured on a vertical spindle shaft 41, mounted in a post 42, projecting upwardly from the frame of the range below the center of the burner openings 13 and 14. Double bevel gear 40 is driven by a bevel gear 43 which meshes with the lower beveled portion of gear 40 and is non-rotatably secured on the inner end of a longitudinally extending shaft 44, mounted in bearings 45 and 46, in the upwardly projecting ends of brackets 47 and 48 which are secured to the frame of the range 10 by suitable means. The shaft 44 is in the plane of the camshaft 26 and has a beveled gear 49 non-rotatably secured on its outer end. Beveled gear 49 is adapted to mesh with the rearmost of two beveled gears 50 and 51 non-rotatably secured on a transversely extending operating shaft 52. Shaft 52 is journaled for rotary and reciprocatory movement in suitable bearings 53 and 54, carried in the upwardly extending arms of a pair of U-shaped members 55 and 56 which are secured by suitable means to the frame of the range adjacent its front and rear ends. The other beveled gear 51, on shaft 52, is adapted to mesh with the bevel gear 49 on the outer end of the shaft 44 of the operating unit associated with the front burner of the range.

The beveled gears 50 and 51 are so spaced on the shaft 52 that the mechanisms associated with the front and rear burners may both be operated from the shaft independently of each other. When the shaft is pushed inwardly until the gear 50 meshes with the gear 49 on the outer end of shaft 44 associated with the rear burner mechanism, the forward gear 51 is disengaged from gear 49 on the shaft 44 of the mechanism associated with the front burner opening 13. If the shaft 52 is pulled out until the forward gear 51 engages with the gear 49 on the longitudinally extending shaft 44 associated with the front burner mechanism, then the gear 50 is disengaged from gear 49 associated with the rear burner mechanism. Thus it will be seen that the mechanisms for raising and lowering the pins of the front and rear burners may be operated independently of each other from a single operating shaft. The operating shaft 52 extends through the front of the range and has a handle or small knob 57 secured on its outer end for grasping when the shaft is to be operated.

The operation of the device is as follows, assuming that the pins associated with the rear burner are in a depressed position and it is desired to raise them. The handle 57 is grasped,

and the operating shaft 52 is pushed inwardly until the gear 50 engages with the gear 49 on the shaft 44 associated with the rear burner mechanism. The operating shaft 52 is then rotated in either direction, thereby rotating gear 50 and causing gear 49, shaft 44 and gear 43 to be rotated. Double bevel gear 40 is rotated by gear 43, and it drives the gears 36, 37, 38 and 39 on camshafts 26, 27, 28 and 29 which mesh with it, thereby causing all the cams to be rotated in synchronism. When the cams have been rotated sufficiently to bring the humped portions of the cams into elevated position, all of the pins will be in elevated position projecting above the top surface of the plate and bearing against the sides of a vessel on the plate adjacent its bottom as shown in Fig. 1. In this position the pins securely hold the bottom of a vessel against lateral movement on the range. By rotating the operating handle further the cams are rotated to a position where the pins are allowed to drop, so that their upper ends are flush with the top of the plate as shown in the left half of Fig. 3. Thus it will be seen that I have provided means for raising and lowering the pins 21 in unison.

The mechanism associated with the front burner is operated in a similar manner, the operating shaft being pulled out until the gear 51 thereon meshes with the gear 49 on the outer end of the shaft 44 associated with the front burner mechanism. A similar arrangement of parts is provided for each bank of front and rear burners in the range. To further secure vessels 35 to the range, they may be lashed to the side rails 11 by lash ropes or straps 58 as shown in Fig. 1.

Each of the arms 15, 16, 17 and 18 in the plates 12 is provided with a plurality of apertures 20, so that the pins 21 may be manually moved as desired for increasing or decreasing the space between the pins to accommodate cooking vessels of various sizes and shapes. If a large vessel is to be placed on the range, the pins are placed in the outer apertures in each arm of the plate, and if the vessel is of small diameter, the pins are moved to apertures closer to the center of the burner opening.

In Figs. 7 and 8, is diagrammatically illustrated a modification of the invention of simplified construction. In place of gear 40, I have provided a driving gear 59 having a single beveled portion. Gear 59 is mounted on a vertical spindle shaft 41 suitably secured in a post 42 projecting upwardly from the frame of the stove below the center of a burner opening. A spur gear 60, mounted on spindle shaft 41, is secured to the main driving gear 59, and is actuated by a rack 61 secured on a transversely extending operating rod 62. Rod 62 is mounted for reciprocatory movement in the upstanding ends of a pair of brackets 63 and 64 which are secured by suitable means to the frame of the range adjacent its front and rear ends. Rod 62 has a second rack 65 secured near its forward end for operating the front burner mechanism. The forward end of the rod projects beyond the front of the range and has a handle or small knob 66 secured on its outer end for grasping by an operator.

The racks 61 and 65 are adapted to mesh with the spur gear 60 on the pot-holding mechanism associated with the rear and front burner respectively, for driving these mechanisms when the rod is pushed in or pulled out. When it is desired to raise or lower the pins 21 in the plate

12 associated with a rear burner opening 14, the operating rod 62 is pushed inwardly until the rack 61 engages with the spur gear 60 on the vertical spindle shaft 41. Upon further inward movement of the rod 62 the spur gear 60 is rotated, and with it the driving gear 59. Gear 59 drives the bevel gears 36, 37, 38 and 39 on the camshafts 26, 27, 28 and 29, thereby rotating the cams and raising or lowering the pins 21 as the case may be.

5 In a range using this modified form of my invention the front burner 13 in each bank of burners is provided with a mechanism similar to that just described for the rear burner. The modification of the invention just described has certain advantages over the modification first described. Double bevel gear 40, bevel gears 43, 49, 50 and 51 and shaft 44 are eliminated, and a rack 61 and spur gear 60 substituted to perform the same 15 function.

20 For purposes of illustration, my invention has been more or less specifically described as applied to a mobile army field range. It will be obvious that it is adaptable for use on other types of 25 stoves and ranges which are to be transported from place to place and may be subject to jostling during transportation, for example, the ranges used in railroad kitchen cars and the ranges used in the galleys of ships and aircraft. These, and 30 other applications of the invention, making use of the principles disclosed herein, are intended to be included in the claims.

35 Having thus described my invention, what I claim as new and desire to secure by Letters Patent is as follows:

1. Means for holding cooking vessels in position on a mobile field range having a top plate with burner openings therein and apertures associated with said openings comprising a plurality of stops spaced in vessel holding relation in said apertures, means for supporting said stops in said apertures, said means being adjustable between a position in which said stops are supported in elevated position projecting above the top surface of said plate and bearing against the sides of a vessel placed thereon for preventing lateral movement thereof, and a position in which said stops are flush with the top of said plate.

2. Means for preventing lateral shifting of 50 cooking vessels on the top surface of a mobile field range having one or more heating plates and one or more sources of heat under each plate comprising one or more groups of spaced vessel-holding stops in each of said plates for securing one or more cooking vessels on said plates over the sources of heat, means individual to each of said groups for operating said stops, said means being adjustable between alternate positions for causing said stops to be moved into or out of operative vessel holding position, and means for operating said adjustable means, said means having independent elements and common elements cooperating with said independent elements to permit the vessel holding means in each group to be moved independently into or out of operative position.

3. Means for holding cooking vessels in position 70 on the top of a mobile field range comprising a top burner plate having a plurality of burner openings therein and a plurality of apertures spaced about said openings, a plurality of stops spaced in vessel holding relation in the apertures of said plate, means for supporting said stops in said apertures, said means being adjustable between alternate positions for moving said stops

into and out of operative vessel holding position, and means for operating said stop supporting means, said means being adapted to operate the supporting means for each burner opening independently of the supporting means for the other burner openings in said plate.

4. Means for holding a cooking vessel in position on a mobile field range comprising a top plate having burner openings and a plurality of apertures therein, said apertures being located on center lines extending radially from the center of said burner openings, the corresponding apertures on said center lines being spaced equi-distant from the center of said burner openings, a plurality of stops spaced in vessel holding relation in said apertures and projecting above the top of said plate for bearing against the sides of a vessel on said plate to prevent lateral movement thereof, said stops being manually adjustable to various positions for accommodating vessels of various sizes and shapes.

5. Means for holding a cooking vessel in position on the top of a mobile field range comprising an apertured top plate, a plurality of stops adapted to be received in said apertures in spaced relation for engaging the sides of a cooking vessel on said plate, a plurality of cams under said top plate, said cams being adapted to support said stops alternately in raised position elevated above the top surface of said plate for confining a cooking vessel therebetween or in retracted position with said stops flush with the top of said plate, and means effective to operate said cams in synchronism for moving said stops in unison into or out of vessel holding position.

6. A holder for use on a mobile field range for holding cooking vessels on the top of said range comprising a top plate having a plurality of apertures therein, a plurality of stops spaced in vessel holding relation in said apertures, means for supporting said stops in said apertures said means being movable from a position in which said stops project above the top surface of said plate and bear against the sides of a cooking vessel placed thereon to prevent lateral movement thereof to a position in which said stops are flush with the top of said plate, said stops being adapted to be manually rearranged in said apertures to accommodate vessels of various cross-sectional areas.

7. Means for holding a cooking vessel in position on a mobile field range comprising a top plate having a plurality of apertures therein arranged in groups, the apertures in each group being radially and concentrically disposed, a plurality of stops spaced in vessel holding relation in said apertures, radially extending means under said top plate for supporting said stops, said means being adapted to move said stops into and out of operative vessel holding position.

8. Means for holding a cooking vessel in position on a mobile field range comprising a top plate having burner openings and a plurality of apertures therein, said apertures being located on center lines extending radially from the center of said burner openings, the corresponding apertures

on said center lines being spaced equidistant from the center of said burner openings, a plurality of stops spaced in vessel holding relation in said apertures and projecting above the top of said plate for bearing against the sides of a vessel on said plate to prevent lateral movement thereof, said stops being manually adjustable to various positions for accommodating vessels of various sizes and shapes, and means for supporting said stops in elevated position projecting above the top of said plate said means being adjustable to permit lowering of said stops to a position flush with the top of said plate.

9. Means for preventing lateral shifting of a cooking vessel on the top of a mobile field range comprising a plurality of spaced vessel-engaging stops, said stops being adapted to be moved between a depressed position flush with the top of said range and an elevated position projecting above said top for engaging the sides of a vessel on said range to prevent lateral shifting thereof, stop-supporting means adjustable between alternate positions for moving said stops into and out of operative vessel-holding position.

10. Means for preventing lateral shifting of a cooking vessel on the top of a mobile field range comprising a plurality of spaced vessel-engaging stops, said stops being adapted to be moved between a depressed position flush with the top of said range and an elevated position projecting above said top for engaging the sides of a vessel on said range to prevent lateral shifting thereof, stop-supporting means adjustable between alternate positions for moving said stops into and out of operative vessel-holding position and means for operating said stop-supporting means.

11. Means for preventing lateral shifting of a cooking vessel on the top of a mobile field range comprising a plurality of spaced vessel-engaging stops, said stops being adapted to be moved between a depressed position flush with the top of said range and an elevated position projecting above said top for engaging the sides of a vessel on said range to prevent lateral shifting thereof, and being manually adjustable to accommodate vessels of various sizes and shapes, and stop-supporting means adjustable between alternate positions for moving said stops into and out of operative vessel-holding position.

12. Means for preventing lateral shifting of a cooking vessel on the top of a mobile field range comprising a plurality of spaced vessel-engaging stops, said stops being adapted to be moved between a depressed position flush with the top of said range and an elevated position projecting above said top for engaging the sides of a vessel on said range to prevent lateral shifting thereof, said stops also being manually adjustable to vary the space there-between for accommodating vessels of various sizes and shapes, stop-supporting means adjustable between alternate positions for moving said stops into and out of vessel-holding position, and means for operating said stop-supporting means.

13. Means for preventing lateral shifting of a cooking vessel on the top of a mobile field range comprising a plurality of spaced vessel-engaging stops, said stops being adapted to be moved between a depressed position flush with the top of said range and an elevated position projecting above said top for engaging the sides of a vessel on said range to prevent lateral shifting thereof, stop-supporting means adjustable between alternate positions for moving said stops into and out of operative vessel-holding position, and means for operating said stop-supporting means.

GEORGE P. WELLS.
